UNITED STATES PATENT OFFICE.

CARL GABRIELSON, OF SYRACUSE, NEW YORK, ASSIGNOR TO L. C. SMITH & BROS.
TYPEWRITER CO., OF SYRACUSE, NEW YORK, A CORPORATION OF NEW YORK.

RIBBON SPOOL FOR TYPEWRITING MACHINES.

Application filed April 14, 1922. Serial No. 552,771.

To all whom it may concern:

Be it known that I, CARL GABRIELSON, a citizen of the United States, and residing at Syracuse, Onondaga County, State of New York, have invented certain new and useful Improvements in Ribbon Spools for Typewriting Machines, of which the following is a specification.

The present invention relates to typewriting machines and particularly to typewriter ribbon spools.

In Patent No. 929,933 granted August 3, 1909, to the present applicant, a typewriter ribbon mechanism is disclosed by means of which the ribbon is automatically advanced across the printing point, being unwound from one ribbon spool and wound up upon a second ribbon spool, the mechanism being designed and constructed so that the rotation of the spools is reversed, and hence the movement of the ribbon, when the delivering spool has become completely empty. The spools illustrated in this patent are, however, intended for continuous use with the machine, the fresh ribbons being wound thereon to replace used ribbons. The removal of a worn out ribbon and its replacement by a fresh ribbon involves the expenditure of time on the part of the operator and it is the object of the present invention to prevent this loss of operating time by providing an inexpensive ribbon spool which may be supplied to typewriter operators with a length of ribbon wound thereon and which spool may be quickly substituted for a spool of worn out ribbon, this last mentioned spool being then discarded. The spool has a number of novel features of construction and the invention may be embodied in various structures. In the present application one form is fully disclosed by way of example.

In the drawings:

Fig. 1 is a vertical section through a ribbon spool shaft showing the improved spool mounted thereon and the ribbon reversing mechanism which cooperates with the spool;

Fig. 2 is a top plan view of the same with spool removed but its operative position indicated in dotted lines;

Fig. 3 is a view similar to Figure 2, the parts being shown however in the positions which they occupy when the spool is in place;

Fig. 4 is a section on line 4—4 of Figure 3;

Fig. 5 is a bottom plan view of the spool;

Fig. 6 is a top plan view of the blank which forms the top flange of the spool;

Fig. 7 is a top plan view of the blank which forms the bottom flange of the spool;

Figs. 8 and 9 are sections on lines 8—8 and 9—9 of Figures 6 and 7 respectively;

Fig. 10 is a plan view of the blank form in which the core of the spool is formed;

Fig. 11 is an edge view of the same;

Fig. 12 is a longitudinal section through a sleeve which forms portion of the spool;

Fig. 13 is an end view of the same;

Fig. 14 is a perspective view of portion of the ribbon reversing mechanism;

Fig. 15 is a plan view of the core of the spool just prior to assembly with the top and bottom flanges thereof; and

Fig. 16 is a section taken axially through a portion of the spool and drawn to a relatively large scale to show the manner in which the parts are secured together.

The main members of the ribbon reversing mechanism and their modes of operation are fully described in my prior patent above mentioned, and only so much of the ribbon mechanism is illustrated in the drawings as is necessary to understand the manner of its cooperation with the improved ribbon spool which is disclosed. It will also be understood that the ribbon spools at both ends of the typewriter are similar and the parts of the ribbon mechanism immediately associated with such spools, so that it is only necessary for a complete understanding of the present invention to illustrate and describe one ribbon spool and its associated mechanism.

A corner of the frame of the machine is indicated at 10, which frame is provided with a stepped recess 11 having a central boss 12 provided with a vertical axial aperture 13 in which the ribbon spool shaft 14 is rotatably supported. Shaft 14 has at its lower end a beveled gear 15 which faces downwardly and which is adapted to mesh with a beveled pinion 16 on the vertically movable drive shaft 17 which extends from front to rear of the machine and which is given a step by step rotary movement by mechanism controlled by the operation of the keys. The upper end of shaft 14 is

provided with an integral collar 18 having two diametrically opposed and upwardly extending teeth 19 thereon, and also has an axial internally threaded cylindrical recess 22.

A thumb screw is provided for detachably securing in place the ribbon spool "S", the threaded spindle 21 of the thumb screw extending through a central opening 23 in the top flange 24 of the spool and the under surface of the thumb screw bearing upon the margin of this opening and upon the upper end of sleeve 25 which surrounds the spool shaft 14 and the upper end of which extends through opening 23 in flange 24. This sleeve is provided adjacent its upper end with an annular flange 26 and is secured to the flange 24 in any suitable manner, as by welding or by a force fit. The lower end of the sleeve rests upon collar 18 of shaft 14, and is provided with suitable notches to receive the two teeth 19 extending upwardly from the collar.

The core of the spool "S" comprises a cylindrical member 27 having upwardly extending flanges 28 at its upper end which extend through openings 24 in the upper flange 24 of the spool, and having downwardly extending flanges 29 at its lower end which extend through openings 30 in the lower flange 30 of the spool. It will be seen that there are three upper flanges 28 and four lower flanges 29 and that one flange in each set is formed in two half portions located at the ends of the member 27, as shown in Figs. 10 and 15. The two parts of each of these split flanges extend through a single opening in the adjacent spool flange and the ends of member 27 are thereby secured in substantial abutment. The flanges 28 and 29 are headed over, as shown in Fig. 16, so that the three main portions of the spool are firmly secured together. The core has a horizontally disposed elongated slot or opening 31. The bottom flange 30 is provided with a plurality of depressed portions 32 which are elongated and the inner surfaces 33 of which comprise cam surfaces, adapted to coact with a moving member mounted on the frame of the machine when the spool is being placed in position, as will hereinafter be more fully explained.

Secured to the bottom of the cup-shaped depression 11 is a plate 35 which is substantially U-shaped and which is provided with parallel downwardly extending arms 36 which pass through an opening 37 in the frame. Pivotaly supported between these arms 36 is a rocker 38 which has an upwardly extending lever arm 39 and a downwardly extending lever arm 40. Lever arm 39 has a horizontal portion 41 at its upper end which is horizontally opposite aperture 31 in the spool and which cooperates there-

with in effecting the reversal of the ribbon spool at the proper time. Portion 41 is cam-shaped, as shown, and a spring 42 which has one end secured to plate 35 and the other end bearing upon the upper edge of the rocker 38 normally tends to force the cam 41 outwardly. Such outward movement is prevented by the ribbon wound on the spool so long as such ribbon is present, but with the unwinding of the last coil of ribbon from the core, spring 42 becomes effective to move the cam 41 outwardly through opening 31.

Outward movement of the lever 39 of course, results in rotation of rocker 38 so that the horizontally extending tooth 43 finds its way between the teeth of the rotating pinion 16 which, of course, has been disengaged from gear 15 while the spool illustrated has been the feed spool or the unwinding spool. Continued rotation of shaft 17 in the direction of the arrow (Figure 1) results in upward movement of pinion 16 and shaft 17 and at an intermediate point in its upward travel a snapover mechanism (not illustrated) becomes effective to quickly move it into engagement with gear 15. The spool illustrated is then operatively connected to shaft 17 and becomes the driven spool, its direction being reversed, and withdrawing ribbon from the spool at the opposite end of the machine, which spool has been operatively disconnected from the driving mechanism simultaneously with the operative connection to this mechanism of the spool illustrated.

When the ribbon has become exhausted a fresh ribbon is substituted by removing that spool upon which the old ribbon has been completely wound and replacing it by a new spool having a fresh ribbon. To remove the old spool the thumb nut 21 is unscrewed and the spool lifted vertically upward, the end 41 of lever 39 moving inwardly as its edge rides over the lower edge of aperture 31 and the inner edge of the bottom flange 30. As soon as the spool has been removed spring 42 immediately tends to return cam 41 to the position in which it is illustrated in Figure 1, in which position it would interfere with the emplacement of a new spool.

Means is provided, therefore, for moving the upper end 41 of lever 39 inwardly toward shaft 14 when the spool is removed. This means comprises a lever 50 mounted to swing or revolve about a vertical axis 51 and provided with a coil spring 52, one end of which bears against plate 35 and the other end against the downwardly extending flange 53 of lever 50, which comprises an abutment therefore. Spring 52 acts on lever 50 in such manner that the end 54 of this lever tends to constantly engage lever 39 and to force this lever toward shaft 14, the

spring 52 being considerably stronger than spring 42 and able to overcome the opposition of this last mentioned spring. The opposite end of lever 50 has a flange or extension 55 projecting vertically upward and adapted to extend within the core of the spool as shown in Figures 1 and 4.

When the spool is lifted from the machine the parts assume the positions in which they are illustrated in Figure 2. In replacing the spool it is lowered over the shaft 14 until the lower surface of its bottom flange strikes the upward projection 55 of lever 50, the cam 41 being held of course, by this lever in its innermost position. The spool is then rotated about its axis until the end of flange 55 lies between two of the cams 32 of the spool and upon further rotation of the spool in either direction flange 55 is moved inwardly by one of the cam surfaces 33 into such position that it may enter a core, as shown in Figure 3, and when it has reached this position, the spool will drop to its lowermost or final position. The ribbon may now be attached to the spool at the opposite end of the machine. Rotation of lever 50 in a clockwise direction as just described, of course, allows cam 41 to move outwardly to operatively engage the inner surface of the spool.

In Figures 5 to 13 inclusive, the various component parts of the spool are illustrated before assembly. The top and bottom flanges and core are stamped from sheet metal, the top flange having central and marginal stiffening ribs 60 and 61, respectively, and the bottom flange being provided with the cams 32. At one end the blank is provided with an integral point or catch 63 which is slightly offset and which is sufficiently sharp to serve to catch and hold the end of the ribbon. In Figure 15 the core is illustrated just prior to assembly with the top and bottom flanges, which assembly is effected preferably by heading over the tops of the tongues extending therefrom but may be done otherwise if desired, as by welding.

From the foregoing description of the invention one skilled in the art will appreciate the advantages of the invention, and will realize that it may be modified considerably without departing from its spirit and scope.

Having thus described the invention what is claimed as new and desired to be secured by Letters Patent is:

1. A typewriter ribbon spool having a

core and top and bottom flanges, the bottom flange having a central aperture, and a cam surface facing said central aperture and inclined to a radius passing therethrough from the center of said aperture, for directing a cooperating member toward the central aperture when the spool is rotated on a ribbon spool shaft.

2. A typewriter ribbon spool having a core and top and bottom flanges, the bottom flange having a central aperture and oppositely directed cam surfaces each facing toward said central aperture and inclined to a radius therethrough from the center of the aperture, for directing a cooperating member toward said central aperture when the spool is rotated in either direction on a ribbon spool shaft.

3. A typewriter ribbon spool having a hollow core and top and bottom flanges, the bottom flange having a central aperture registering with the hollow core and being provided with a cam surface facing toward the aperture and extending outwardly from a point on the edge of said central aperture.

4. A typewriter ribbon spool having a hollow core and top and bottom flanges, the bottom flange having a central aperture registering with the hollow core, and being provided with two oppositely facing cam surfaces extending outwardly from the central aperture.

5. A typewriter ribbon spool having a hollow core, and top and bottom flanges, the bottom flange having a central aperture registering with the hollow core, and being provided with four cams arranged at equal intervals around the central aperture, each cam having two cam surfaces substantially tangent to the central opening at a common point and extending outwardly therefrom.

6. A typewriter ribbon spool including upper and lower flanges and a central core, said core comprising a curved metallic strip provided with flanges along its upper and lower edges which extend through apertures in the upper and lower flanges of the spool, each corner of the strip being provided with one of said flanges and the two upper corner flanges extending through a single aperture in the upper spool flange and the two lower corner flanges extending through a single aperture in the lower spool flange, whereby the ends of the strip are held in substantial abutment.

In testimony whereof I hereunto affix my signature.

CARL GABRIELSON.
